UNITED STATES PATENT OFFICE.

WILLIAM K. KIDDER, OF NEW YORK, N. Y.

SWIMMING APPARATUS.

SPECIFICATION forming part of Letters Patent No. 250,077, dated November 29, 1881.

Application filed September 24, 1881. (No model.)

To all whom it may concern:

Be it known that I, WILLIAM K. KIDDER, of New York, in the county of New York and State of New York, have invented certain new and useful Improvements in Swimming Apparatus; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

This invention consists in a swimming apparatus wherein are combined a buoyant equipment for the upper portion of the human body and a propelling mechanism for attachment to the body, constructed to be operated by the hands or feet, or by both, as hereinafter set forth in detail.

20 This invention is illustrated in the accompanying drawings, in which Figure 1 represents a front view, partly in section. Fig. 2 is a longitudinal section on the line $x-x$, Fig. 1. Fig. 3 is a detail view, showing the arrangement 25 of the propeller ropes and springs. Fig. 4 is a detail view of a cap forming an alternative attachment of the apparatus, as hereinafter explained. Fig. 5 is a rear view of the truss.

Similar letters of reference indicate corresponding parts.

30 The letter A designates a series of bands or straps adapted to be fastened to the upper portion of the human body and supporting two side floats, B, thus forming what is commonly known as a "life-preserver."

35 C designates a waistband, usually having connected thereto a crotch-band, C', and serving to support the propeller-wheels D D' D² and mechanism upon the body. This waistband C and crotch-band C' are connected together at the back by a cord, C³, (see Fig. 5,) 40 passing through loops at the ends of the waistband, and also through loops in the crotch-band, the whole forming a truss.

45 The propeller-wheels D D' D² are arranged at the ends of a T-shaped frame, E E', and connected to bevel-gear having in turn connected thereto hand-ropes F and foot-ropes G, for imparting thereto and thence to the propeller-wheels a revolving motion. The said bevel-gear consists of a cog-wheel, 5, fixed to

one end of a shaft, 6, which extends through the longitudinal member E of the propeller-frame, and to the opposite end of which is fixed the propeller-wheel D; further, of two cog-wheels, 7, geared with the wheel 5 and fixed to one of the ends of the shafts 8, which extend outward through the two limbs E' of the transverse member of the propeller-frame, and to the other or outer ends of which are fixed 55 cog-wheels 9; and, further, of cog-wheels 10, geared with the wheels 9, and fixed to one of the ends of shafts 11, to the other ends of which are fixed the propeller-wheels D' D², respectively.

60 Both the hand ropes or straps F and foot ropes or straps G are connected to the ropes or straps H, Fig. 3, by windlasses I, which are fixtures of the cog-wheels 7, and if the ropes F G are alternately pulled to and fro, the windlass-ropes H are alternately wound and 65 unwound, thus giving motion to the bevel-gear and the propelling-wheels. The motion thus produced, however, is in reverse directions, and in order to adapt the propeller-wheels D D' D² 70 to act continuously in the one and the same direction, they are constructed to be reversed automatically, as hereinafter explained.

75 The hand-ropes F are provided with handles 13, and the foot-ropes G with pedals 14, while both sets of ropes are provided with retractile 80 springs 15 or 16—that is to say, the springs 15 of the hand-ropes have a tendency to draw the same in an upper direction, and the springs 16 of the foot-ropes to draw the same also in an 85 upper direction, so that by these springs the operation of the ropes is materially facilitated by being kept continuously strained.

85 The limbs E of the propeller-frame are secured to a plate, J, covering the windlasses, by 90 screws 18 or other suitable means, and are thus rendered detachable, so that, if desired, the propeller-wheels D' D² may be omitted, and in order to permit the ready application of these parts the shafts 8 are provided with coupling-clutches 17.

95 The plate J is hinged or otherwise attached to a box, J', which is detachable and adjustably connected to a bracket, K, (see Fig. 2,) which is a fixture of the waistband C.

100 When the limbs E are detached for the purpose of dispensing with the propeller-wheels

D' D², the plate J can be removed and a cap, Fig. 4, be substituted therefor, if desired.

The limbs E' of the propeller-frame, moreover, are connected to the longitudinal limbs 5 E thereof by hinge-joints 19, while the limb last named is made in sections, which are connected together by a hinge-joint, 20, so that the frame is adapted to be folded together, thus bringing the whole into a small compass, the 10 shaft 6 also being provided with a clutch, 23, Fig. 3.

The propeller-wheels D D' D² are composed of blades 21, which are swiveled to a head, 22, allowing them to change their positions, and 15 provided with suitable stops for determining the positions thereof. The particular construction of these wheels, however, forms no part of my present invention, and I reserve the right to make the same the subject-matter of 20 separate applications.

Floats N, of cork or other suitable material, are connected to the limbs E of the propeller-frame to co-operate with those of the life-preserved, said floats N being preferably made 25 flexible.

Having thus described my invention, what I claim as new, and desire to secure by Letters Patent, is—

1. The combination, substantially as herein-before set forth, of the life-preserved, the propeller-wheels, the T-shaped propeller-frame, the bevel-gear acting on the propeller-wheels, the hand ropes or straps, and the foot ropes or straps, for the purpose specified. 30

2. The combination, substantially as herein-before set forth, of the life-preserved, the propeller-wheels, the propeller-frame constructed with the detachable limbs E', the bevel-gear acting on the propeller-wheels, the hand ropes or straps, and the foot ropes or straps. 35

3. The combination, substantially as herein-before set forth, of the life-preserved, the propeller-wheels, the propeller-frame, the bevel-gear acting on the propeller-wheels, the hand ropes or straps, the foot ropes or straps, the 40 hand-rope springs, and the foot-rope springs. 45

In testimony that I claim the foregoing I have hereunto set my hand this 22d day of September, 1881.

WILLIAM K. KIDDER.
